UNITED STATES PATENT OFFICE.

WILLIAM HORNSBY AND DAVID ROBERTS, OF GRANTHAM, ENGLAND.

STEAM-GENERATOR.

SPECIFICATION forming part of Letters Patent No. 680,593, dated August 13, 1901.

Application filed March 18, 1901. Serial No. 61,716. (No model.)

To all whom it may concern:

Be it known that we, WILLIAM HORNSBY and DAVID ROBERTS, subjects of the King of Great Britain, residing at Spittlegate Iron 5 Works, Grantham, England, have invented new and useful Improvements in Steam-Generators, of which the following is a specification.

This invention relates to improvements in 10 steam-generators, and has for its object to insure the development of more power upon a given floor-space and also greater efficiency than is possible with steam-generators as heretofore usually made.

15 The invention is applicable to steam-generators of the water-tube type, as constructed with a series of straight, inclined, or curved tubes over a furnace, either or both ends being suitably connected to a steam and water 20 drum or drums.

According to this invention we arrange one or more furnaces, each with its own ash-pit, below the usual furnace and ash-pit, the gases 25 from the lower furnace or furnaces passing into and through the combustion-chamber and thence over the heating-surface of the boiler. To obtain more heating-surface, we make the headers with extra rows of tubes in height or depth, and we may also arrange 30 over the lower furnace or furnaces one or more rows of tubes, which may be connected to the usual slab or sectional headers so as to form part of the boiler. On some of the tubes over the furnace we place fire-clay tiles 35 or specially-shaped fire-clay bricks, so as to cause the gases to travel over the bridge-wall of the furnace into the combustion chamber or chambers before passing upward over the heating-surface of the boiler. A series of 40 suitable baffles is arranged so as to cause the gases of combustion to circulate over the whole of the heating-surface (and superheater, if used) before passing to the chimney.

When boilers such as those previously 45 described are fitted with superheaters, instead of placing the superheater in the usual position—*i. e.*, immediately under the steam-drum and above the tubes and using one stack of tubes—we divide the tubes into two stacks 50 and place the superheater between them, so that it will be subjected to the action of hot-

ter gases of combustion than it would be when placed in the ordinary position.

In the accompanying drawings, Figure 1 is a sectional elevation of a steam-generator 55 having our improvements applied thereto. Fig. 2 is a cross-section on the line 2 2, Fig. 1. Fig. 3 is a cross-section on the line 3 3, Fig. 1. Fig. 4 is a front elevation of the generator. Fig. 5 is a view, similar to Fig. 1, of a 60 generator having a superheater arranged according to the invention. Fig. 6 is a cross-section on the line 6 6, Fig. 5. Fig. 7 is a cross-section on the line 7 7, Fig. 5, and Fig. 8 is a front elevation of the generator. 65

Referring first to the arrangement illustrated in Figs. 1 to 4 of the drawings, *a* is the upper furnace of the generator, and *b* is its ash-pit. *c* is the lower furnace, and *d* the ash-pit thereof, said furnaces having in rear thereof a common combustion-chamber, as shown. These two furnaces are arranged one directly above the other, and the fire-clay tiles *e e*, forming a deflecting-plate, are placed above both furnaces to cause the gases from both 75 upper and lower furnaces to pass over the bridges and into and through the combustion-chamber and thence over the heating-surface of the boiler in the usual manner. *f* is the steam and water drum, *g g* are the water-tubes over the upper furnace *a*, and *h* and *i* the front and back headers, respectively, to which the said tubes are connected. *j j* are the tubes arranged between the upper and lower furnaces. *k* is the front header and *l* the 80 back header and mud-drum, to which the said tubes are connected. The header *h* is connected to the steam and water drum *f* by the nipples *m m* and to the header *k* by the tubes *n n*, while the header and mud-drum *l* are connected to the header *i* by the tubes *o o* and to the steam and water drum *f* by the tubes *p p*. 85

Referring now to the arrangement shown in Figs. 5 to 8, the same letters of reference designate the same parts as in Figs. 1 to 4, 95 and the arrangement of the furnaces, ash-pits, combustion-chambers, stoking-levels, and boiler generally is also the same, with the exception that the headers *h* and *i* and tubes *g* are divided into two stacks, the divided headers being connected by the nipples *q q* and *r r*, respectively. *s* is the su- 100

perheater, placed between the stacks of tubes *g*. *t* is the steam-inlet and *u* the steam-outlet from the superheater. *v* and *w* are stop-valves, and *x* is the steam-supply pipe from the generator. By regulating the stop-valves *v* and *w* either saturated, superheated, or mixed steam passes into the said supply-pipe *x*. By arranging the superheater between the divided stack of tubes it will be subjected to the action of hotter gases than is the case when it is placed immediately under the steam and water drum in the usual manner.

Having now particularly described and ascertained the nature of our said invention and in what manner the same is to be performed, we declare that what we claim is—

1. In a steam-generator, the combination with two furnaces arranged one above the other and a common combustion-chamber communicating with both furnaces, of a boiler comprising a steam-drum, a water-tube section located above the upper furnace and connected with the steam-drum and a water-tube section interposed between said furnaces, connections extending therefrom to the upper water-tube section from said lower tube-section directly to the steam-drum, substantially as described.

2. In a steam-generator, the combination with two furnaces arranged one above the other and a common combustion-chamber communicating with both furnaces, and a deflecting-plate above each furnace extending from the front thereof to the combustion-chamber, of a boiler comprising a steam-drum, a water-tube section located above the upper furnace and connected with the steam-drum, a water-tube section located above the lower

furnace, connections from said lower water-tube section to the upper water-tube section 40 and direct connections from said lower water-tube section to the steam-drum, said water-tube sections extending rearwardly into and over the combustion-chamber, substantially as described. 45

3. In a steam-generator, the combination with two furnaces, arranged one above the other and a common combustion-chamber communicating with both furnaces, of a boiler comprising a steam-drum an upper water-tube section located above the upper furnace, said section being divided horizontally into two parts and connected with the steam-drum, a superheater arranged between the two parts of the upper water-tube section and connected 55 with the steam-drum, a lower water-tube section interposed between the two furnaces, connections extending therefrom to the upper water-tube sections and direct connections extending from said lower water-tube 60 section to the steam-drum, substantially as described.

4. In a steam-generator, the combination with a furnace and combustion-chamber, of a boiler comprising a steam-drum, a water-tube section formed in two horizontal parts and connected to the steam-drum and a superheater interposed between the parts of the water-tube section and connected with the steam-drum, substantially as described. 70
